UNITED STATES PATENT OFFICE.

DAVID E. WHITE, OF LA GRANGE, ILLINOIS, ASSIGNOR TO ROBERTS AND SCHAEFER COMPANY, OF CHICAGO, ILLINOIS, A CORPORATION OF ILLINOIS.

LOCOMOTIVE CINDER PLANT.

Application filed March 10, 1924. Serial No. 698,185.

To all whom it may concern:

Be it known that I, DAVID E. WHITE, a citizen of the United States, residing at La Grange, in the county of Cook and State of Illinois, have invented a certain new and useful Improvement in Locomotive Cinder Plants, of which the following is a specification.

My invention relates to means for simultaneously removing and disposing of the cinders of a plurality of locomotives, with maximum speed and ease. In railroad yards where locomotives are being handled, it is important to be able quickly and simply to remove the cinders from a locomotive and to handle a number of locomotives at once. The purpose of this invention is to provide a simple, cheap, compact and safe means for removing and depositing the cinders of locomotives which shall avoid the risks and disadvantages of the familiar open, water-filled cinder pits, which are dangerous to the employees, expensive to install, expensive and inefficient to operate and wasteful of space. I illustrate my invention in the accompanying drawings, wherein—

Figure 1 is a side elevation with parts in section;

Figure 2 is an end view of the device shown in Figure 1;

Figure 3 is a plan view;

Figure 4 is a section on the line 4—4 of Figure 1;

Figure 5 is a plan view of a variant form;

Figure 6 is a side elevation with parts in section; and

Figure 7 is a section on the line 7—7 of Figure 6.

Like parts are indicated by like symbols throughout the specification and drawings.

A is any suitable tower or elevated structure herein diagrammatically illustrated as having the foundations A¹, the vertical frame members A² and the transverse frame members A³.

Mounted at the top of the tower is the chute B terminating in the reduced portion or spout B¹ having hinged to the end a terminal spout element B². The spout may be rigidly secured to the top of the tower A and may be supported by the supplemental braces B⁵, B⁶ extending outwardly from the tower and the cross support B⁷ which is associated with the vertical support B⁸ supporting the outer and lower end B¹ of the

chute. B⁹ is any suitable upwardly and outwardly extending brace or support upon the end of which is mounted the pulley B¹⁰, about which passes the cable B¹¹, one end of which is secured to the outer end of the hinged chute element B². The opposite end of the cable B¹¹, which passes about the pulley B¹², is provided with the counter weights B¹³. Preferably the weight of the chute B² and the counterweights B¹³ balance, and any suitable means may be provided for raising and lowering the hinged chute element B².

C is a cinder car track upon which may be located the car to receive the cinders deposited by the locomotives. This track is so positioned in relation to the chute B² that when B² is in lowered position it is adapted to feed cinders directly over the track and into the cars which may be passed therethrough. C¹, C² are the locomotive supporting tracks which are herein illustrated as parallel with the track C, the tower A being herein shown as located between the tracks C¹ and C², although obviously I do not limit myself to any specific location of the tower or support provided that the structure is suitably located and supported to carry out my purpose.

The tracks C¹, C² are each provided with cinder pits D, D¹ at opposite sides of the tower A. These pits may be of any suitable construction, but are herein shown as comprising a slanting bottom D², vertical sides D³, hoppers D⁴ and gates D⁵ hinged thereto, which may be open and shut by any suitable actuating means with the outer opening levers D⁶. Each pair of cinder pits is connected by inclined curved run-ways D¹⁰ which curve or incline together to form a letter Y, and terminate in a sharply inclined wall D¹² located substantially mid-way between the tracks C¹ and C². D¹⁵ is any suitable water connection for wetting down red hot cinders and coals.

Extending upwardly from the incline D¹² to the top of the tower A are the track beams E which support in any suitable manner the track flanges E¹. The track beams are herein shown as coming to an apex as at E² adjacent the top of the tower and just beneath the hoisting housing E⁴ in which any suitable hoisting machinery may be located. The tracks E¹ leave the track beams E adjacent the top of the hoist and join in

a relatively horizontal track section E⁵. Any suitable form of track may be used, and it may be secured to the track beams in any suitable way, but I illustrate in Figure 4 a cross section illustrating a practical track arrangement which has proved satisfactory in actual use. The horizontal track section E⁵ passes directly over the upper or hopper portion of the chute B. The track 10 E¹ is provided with a switch E¹⁰ from which extend branches E¹¹, E¹² beneath the cinder hoppers D⁴. The track members E may be supported by the structural elements E²⁰ outwardly extending from the foundations 15 A¹ and the tower A.

Any suitable power plant may be provided situated at any suitable place, but is herein illustrated as situated in the hoisting housing E⁴. I illustrate, for example, an 20 electric drum hoist G about which passes the cable G¹, each end of the cable being secured to a cinder bucket G² of the shape herein shown with opposed sides G³ and G⁴ inclined in relation to each other and a bottom G⁵ perpendicular to the outer side G⁴. Upon the inclined side G³ are mounted two 25 pairs of wheels G⁸, G¹⁰, the axle supporting the wheels G¹⁰ being of less length than the distance between the track beams E and the axle G¹¹ of the wheels G⁸ being of greater 30 length than the distance between the tracks E. Thus when the bucket reaches the top of the beams E, the lower wheels G⁸ ride upwardly along the track beams, while the upper wheels G¹⁰ ride along the horizontal track E⁵, the effect being to tilt and dump the bucket, as shown in Figure 1. Thus 35 when the bucket leaves the top of the track, it is tilted in the position shown at the top 40 of Figure 1. The third pair of wheels G¹² co-operates with the wheels G⁸ in supporting the bucket upright upon the lower track extensions beneath the cinder hoppers, as 45 shown at the bottom of Figure 1.

It will be understood that the length of the cable G¹ and the weight of the two buckets is such that the buckets balance each other and that when one bucket is dumping at the top of the tower the other is positioned beneath one or the other of the cinder hoppers.

While I have illustrated herein a cinder chute which is fixed against rotation about a vertical axis, I do not limit myself to this type. I illustrate herein two chutes extending outwardly from the tower in opposite sides to deliver cinders to a plurality of tracks, but I may employ a single chute and cinder track. It will be also realized that while I have described this device as a cinder plant, it might also be used to deliver coal, the coal being dropped to the cinder hoppers from the bottom of the coal car and delivered to the locomotive upon the track C.

In the variant form shown in Figures 5,

6 and 7, I illustrate a cinder car supporting track K and four parallel tracks K¹, K², K³, K⁴ adapted to support locomotives during decinderizing. K⁵ is any suitable tower structure herein shown as projecting upwardly 70 between the tracks K and K¹.

L, L are track beams mounted on an incline upon said tower and having mounted thereon tracks L¹, terminating in outwardly curved sections L². The tracks L¹ pass 75 downwardly along the inclined cinder pit wall L³ and extend laterally along the bottom L⁴ of the cinder pit. The end of the rail may be re-curved as at L⁵ to overlie the horizontal section of the rails L¹. L⁶ is 80 the opposed end wall of the cinder pit. It will be seen that the cinder pit passes beneath all four of the tracks K¹, K², K³, K⁴ along an axis transverse to the axis of said tracks.

Underlying each of said tracks are hoppers M similar to those already described, and being provided with gates M¹ and any suitable gate levers M². Adapted to ride on said tracks L¹ and L² is the single dump 90 bucket O having an inclined side O¹ having approximately the inclination of the tracks L¹. The dump bucket is provided with two pairs of wheels O³, O⁴ on the bottom of the bucket and a single pair of wheels O⁵ adjacent the top of the inclined side O¹ of the bucket. O⁶ is any suitable hoisting cable extending about the sheave O⁷ from the top of the tracks L and descending thence to any suitable hoist O⁸, the details of which form 95 no part of the present invention, and are not herein illustrated. O⁹ is an inclined wheel engaging stop projecting upwardly and outwardly and along the beams L. O¹⁰ is any suitable dump baffle plate adapted to 100 direct the cinders into the underlying cinder cars.

While I have illustrated an operative and efficient device, I do not limit myself to the details herein shown and it will be realized 110 that many changes might be made in the number, size, shape and disposition of parts and in the relation and location of the hoppers and the tower and tracks without departing from the spirit of my invention.

The use and operation of my invention 115 are as follows:

It has been in the past customary to provide large open cinder dumps which are frequently kept full of water, which take 120 up a great deal of space, which are very expensive to install, and which risk the lives of the employees who are not infrequently drowned in the open pits into which they sometimes fall, particularly at night. The open pits take up valuable space and the removal of cinders therefrom is inconvenient and expensive. Therefore, in order to avoid these various disadvantages, I have provided a simple, compact, cheap- 125 130

ly constructed locomotive decindering plant which has the additional advantage of being adaptable on emergency for the loading of coal, although it is constructed with 5 a view particularly to decindering a number of locomotives at once or in rapid succession.

Taking, for example, Figure 3, I illustrate four tracks, two upon which the cinder or ash cars may be spotted, the other two tracks upon which locomotives may be spotted. Under ordinary conditions but a single cinder track and chute is necessary. Beneath the two locomotive tracks I place 15 two pairs of cinder receiving hoppers, with the requisite gates in the bottom thereof. Extending from the bottoms of these hoppers are tracks, which join, at a switch beneath the locomotive track level, with a 20 track that passes upwardly to the top of a tower or chute. Mounted on the top of the tower is any suitable material delivering mechanism, herein shown as a chute, adapted to deliver the cinders to a track other than the track upon which the locomotives are spotted. I may increase the 25 capacity of the tower by providing a pair of such hoisting tracks, on opposite sides of the tower, and I increase the efficiency 30 of operation by balancing the buckets or cars which ride upon the hoisting tracks. I can spot four locomotives at once and discharge their cinders into the cinder hoppers, the hoppers being made, if desired, 35 of sufficient size to take the ashes or cinders from more than one locomotive. When the hoppers are filled, or when it is desired 40 to empty them and after the cinders have been watered down in the usual manner I spot a cinder bucket beneath the particular cinder hopper I wish to empty and open the hopper gates and discharge the cinders into the bucket. When either bucket 45 is being so filled the opposite bucket is at the upward extremity of its travel in the dumping position over the hopper end of the chute.

When the first mentioned bucket is filled with the cinders, I actuate the hoisting 50 mechanism, which serves to carry it up to the top of the tower and dump it while at the same time carrying the other bucket into position beneath one or the other of the hoppers situated on the opposite side of the tower. The process of dumping the alternate hoppers may be continuous or substantially continuous, locomotives being 55 spotted over the hoppers, depositing their load of cinders, and passing on, while each cinder bucket receives the load alternately from one or the other of the two cinder hoppers which it serves.

In the form shown in Figures 5, 6 and 60 7, I show a cinder track and a plurality of parallel locomotive tracks with a tower

between the cinder track and the locomotive tracks. This tower is provided with an inclined dumping track L^1 terminating in the outwardly curved section L^2 . The dumping bucket may be aligned beneath any one of 70 the four hoppers M and may receive its load therefrom. The bucket is prevented from overturning in response to any unevenness of load by the overlying tracks L^5 which in combination with the tracks 75 L^1 , engage both the tops and the bottoms of the wheels O^3 and O^4 . When the bucket is drawn upwardly along the tower, the wheels O^5 and O^4 are in contact with the tracks L^1 but the length of the axles 80 of the respective pairs of wheels is such that while the wheels O^4 ride up on the inclined element O^9 the wheels O^5 pass therethrough along the curved section L^2 and the dumping bucket is tilted into the 85 dumping position shown in dotted lines in Figure 6.

It will be understood that the size of the dumping hoppers may be such as to hold 90 a load of cinders from a plurality of locomotives and the cinder bucket may be of such size as to take the cinders from a plurality of hoppers. In any case, the cinder bucket is passed beneath the locomotive tracks and receives the cinders discharged from the hoppers, and removes them laterally away from the locomotive tracks and carries them to the dumping point above the cinder track and there discharges them into the cinder car or any other suitable cinder disposing means. 100

I claim:

1. An installation for handling materials comprising a pair of adjacent tracks, a plurality of hoppers beneath each track, said 105 hoppers on the separate tracks being aligned with each other, a third track adjacent said pair of tracks, a tower between said pair of tracks located between said pairs of hoppers, conveying means for conveying material from each of the hoppers to the top of the tower, and a chute adapted to deliver material from said tower over said third track. 110

2. An installation for handling materials comprising a pair of adjacent tracks, a plurality of hoppers beneath each track, said hoppers on the separate tracks being aligned with each other, a third track adjacent said pair of tracks, a tower between said pair of tracks located between said pairs of hoppers, conveying means for conveying material from each of the hoppers to the top of the tower comprising in part a forked track 115 for each pair of hoppers having a branch underlying each hopper of the pair, and a chute adapted to deliver material from said tower over said third track. 120

3. An installation for handling materials, comprising a pair of adjacent tracks, a plu- 125

rality of hoppers beneath each track, said hoppers on the separate tracks being aligned with each other, a third track adjacent said pair of tracks, a tower between said pair of tracks located between said pairs of hoppers, conveying means for conveying material from each of the hoppers to the top of the tower comprising in part a forked track for each pair of hoppers having a branch underlying each hopper of the pair, and a chute adapted to deliver material from said tower over said third track, and buckets adapted to travel upon said tracks and means for actuating them, the bucket upon one track balancing the bucket upon the other.

4. An installation for handling materials, comprising a pair of adjacent tracks, a plurality of hoppers beneath each track, said hoppers on the separate tracks being aligned with each other, a third track adjacent said pair of tracks, a tower between said pair of tracks located between said pairs of hoppers, conveying means for conveying material from each of the hoppers to the top of the tower comprising in part a forked track for each pair of hoppers having a branch underlying each hopper of the pair, and a chute adapted to deliver material from said tower over said third track, and buckets adapted to travel upon said tracks and means for actuating them, the bucket upon one track balancing the bucket upon the other and driving means for said buckets located at the top of said tower.

5. In a locomotive cinder and coaling plant, a plurality of locomotive receiving tracks, hoppers, positioned beneath said tracks, adapted to receive the cinders discharged from said locomotives, conveying tracks positioned beneath said hoppers, buckets travelling therealong, adapted to receive the cinders discharged from said hoppers and to elevate them to a level substantially higher than the level of said locomotive tracks, a cinder car track located adjacent the locomotive receiving tracks and means for conveying and depositing there-

above the cinders transported by said conveying means.

6. In a locomotive cinder and coaling plant, a plurality of locomotive receiving tracks, a plurality of hoppers positioned beneath each of said tracks, adapted to receive the cinders discharged from said locomotives, conveying means positioned beneath said hoppers and adapted to receive the cinders discharged therefrom and elevate them to a level substantially higher than the level of said locomotive tracks, a cinder car track located adjacent the locomotive receiving tracks, and means for conveying and depositing thereabove the cinders transported by said first mentioned conveying means.

7. The process of decindering locomotives and of disposing of the cinders therefrom, which consists in substantially simultaneously discharging the cinders from a plurality of locomotives, receiving said cinders at a level beneath that of the locomotives, directly conveying said cinders to a level substantially above that of the locomotives and discharging them by gravity above a movable container positioned at a point laterally out of line with the axis of movement of said locomotives.

8. The process of decindering locomotives and of disposing of the cinders therefrom, which consists in substantially simultaneously discharging the cinders from a plurality of locomotives positioned along substantially parallel laterally spaced axes of movement, receiving said cinders at a level beneath that of the locomotives, directly conveying said cinders to a level substantially above that of the locomotives, and discharging them by gravity above a movable container positioned at a point laterally out of line with the axes of movement of said locomotives.

Signed at Chicago, county of Cook and State of Illinois, this 1st day of March, 1924.

DAVID E. WHITE.
